UNITED STATES PATENT OFFICE.

LOUIS B. BENNETT, OF DETROIT, MICHIGAN, ASSIGNOR TO FLORENCE MAY ECKMAN, OF DETROIT, MICHIGAN.

MULTIPLE FUSE.

1,266,095.

Specification of Letters Patent. Patented May 14, 1918.

Application filed March 26, 1917. Serial No. 157,416.

To all whom it may concern:

Be it known that I, LOUIS B. BENNETT, a citizen of the United States of America, residing at Detroit, in the county of Wayne 5 and State of Michigan, have invented certain new and useful Improvements in Multiple Fuses, of which the following is a specification, reference being had therein to the accompanying drawings.

10 The invention relates to fuse fittings of that type in which the fuse is mounted in a screw-plug engageable with a socket fitting in the electric circuit. It is the object of the invention to obtain a construction in 15 which a multiple fuse element is detachably mounted in the plug so as to be replaceable and also adjustable for the successive inclusion of the fuses in circuit. To this end the invention comprises the novel construction as hereinafter set forth.

20 In the drawings:

Figure 1 is a vertical central section through the fitting;

Fig. 2 is a section at right angles to Fig. 1; 25 Fig. 3 is a perspective view of the plug casing;

Fig. 4 is a perspective view of the unit detached therefrom.

A is a screw-threaded contact member, 30 and B is a central contact member of a plug fitting, said contacts being mechanically secured, and insulated from each other by a suitable plastic insulator C. D is a casing projecting outward from the contact A, 35 which is preferably formed of insulating material and is provided with parallel sides between which may be inserted the detachable multiple fuse element E. The latter is formed of suitable insulating material, being provided with a central metallic contact F and a series of contacts G arranged around the periphery thereof. These contacts are preferably in peripheral notches in the insulating material so as to be separated and 40 insulated from each other. H are fuses, which extend radially from the contacts G to the central contact member F, being preferably connected thereto by soldering. The assembly of the parts E, F, G and H may be 45 accomplished in various ways obvious to those skilled in the art, as for example by forming the member E in two halves between which the fuse members H are engaged, the extremities of said members projecting and being soldered or otherwise elec-

trically connected to the parts F and G. I 5 is a thumb-screw which passes centrally through one of the sides of the casing D and engages a threaded aperture in the central contact F. This screw serves to retain the 60 member E in engagement with the casing and also draws the contact member F into contact with a member J which forms an electrical connection between the same and the outer or screw-threaded contact member 65 A. K is a contact member within the hollow plug which is electrically connected with the contact member B and extends to engage one of the peripheral notches in the member E and to form electrical connection 70 with the contact G therein.

With the construction as described, when the plug is engaged with a socket connected into an electric circuit the current will pass from the contact B through the member K 75 to the contact G, thence through the connected fuse H to the central contact F and from the latter through the member J to the outer threaded contact member A, thereby completing the circuit. In case the fuse H 80 is blown it is only necessary to rotate the member E one notch, which will bring into circuit another fuse, and this adjustment can be made from time to time until all of the fuses are destroyed. The member E may 85 then be removed by disengaging the thumb-screw I and a new unit E inserted in place thereof and secured by said screw. Thus the only part to be renewed is the member 90 E, which is comparatively simple and inexpensive in construction.

What I claim as my invention is:

1. A multiple fuse, comprising a plug member having coöperating electrical contacts, a replaceable member detachably connected to said plug member and provided with a central contact, a series of peripheral contacts and radial fuses extending therebetween, and means for detachably connecting said replaceable unit to said plug, 95 forming electrical connection between one of the plug contacts and the central contact of said replaceable member and a connection to the other of said plug contacts for successively engaging the peripheral contacts of the replaceable member in different positions of rotative adjustment thereof. 100

2. In a multiple fuse, the combination with a plug member having socket-engaging contacts, of a replaceable unit de- 105

110

tachably mounted in said plug and provided with a central contact, a series of peripheral contacts and radial fuses therebetween, a contact member on said plug 5 electrically connected with one of said socket-engaging contacts and successively engaging the peripheral contacts on the replaceable member in different positions of rotative adjustment thereof, and an electrical connection between the central contact of 10 said replaceable member and the other of said socket-engaging contacts.

3. In a multiple fuse, the combination with a plug member provided with socket-engaging contacts, or a replaceable unit 15 detachably mounted in said plug member, comprising a peripherally-notched, centrally-apertured insulator body, a contact member in said central aperture, a series of contacts 20 respectively in the peripheral notches and radial fuses therebetween, means for forming electrical connection between one of said socket-engaging contacts and the central contact of said replaceable member, and 25 a member connected to the other of said socket-engaging contacts for successively engaging said peripheral notches and the contact members therein.

4. A multiple fuse, comprising a plug 30 member provided with socket-engaging contacts, a replaceable unit rotatively mounted on said plug on an axis transverse to the axis of the plug, said unit comprising a peripherally-notched, centrally-apertured 35 insulator body, a contact in the central aperture thereof, a series of contacts in the

peripheral notches and radial fuses therebetween, a clamping screw for securing the central contact of said replaceable member to said plug member and for forming electrical connection to one of said socket-engaging contacts, and a member arranged to successively engage the peripheral notches of said replaceable member constituting an electrical connection between the contacts in 40 said notches and the other of said socket-engaging contacts and also yieldably retaining said replaceable member in its adjusted position.

5. A multiple fuse, comprising a plug member, having an insulator body and socket-engaging contacts mounted thereon, said insulator body being provided with outwardly extending parallel walls, a replaceable unit insertible between said parallel 55 walls, comprising a peripherally-notched, centrally-apertured insulator body, a series of contacts in the peripheral notches thereof, a contact in the central aperture and radial fuses therebetween, a pin passing 60 through one of said walls and engaging the central contact of said replaceable unit to retain the same and to establish electrical connection with one of said socket-engaging contacts, and a contact member arranged 65 within said plug for successively engaging the notches of said replaceable member and the contacts therein being connected to the other of said socket-engaging contacts.

In testimony whereof I affix my signature.

LOUIS B. BENNETT.
